UNITED STATES PATENT OFFICE.

LOUIS A. STRAUBEL, ERNEST T. STRAUBEL, AND EDWARD L. STRAUBEL, OF GREEN BAY, WISCONSIN.

MULTIPLE-FUEL CARBURETER.

1,235,396.

Specification of Letters Patent. Patented July 31, 1917.

Application filed March 11, 1913, Serial No. 753,647. Renewed April 13, 1917. Serial No. 161,901.

To all whom it may concern:

Be it known that we, LOUIS A. STRAUBEL, ERNEST T. STRAUBEL, and EDWARD L. STRAUBEL, citizens of the United States, and 5 residing at Green Bay, Wisconsin, have invented a new and useful Improvement in Multiple-Fuel Carbureters, of which the following is a full and accurate description.

Our invention relates to that class of internal combustion engines in which provision is made for burning either gasolene or a heavier oil as kerosene, distillates or alcohol, or any combination thereof. The object of the invention is to produce an engine in which said fuels may be burned interchangeably, that change may be made from one fuel to the other by the simple adjustment of a valve, that the fuel may be aerated or mixed with a quantity of air and 20 then heated to a high temperature, and that cool air may be mixed with the heated vapor in a desired proportion before entering the crank case or combustion chamber of the engine.

We attain these objects by means of the mechanism hereinafter described, reference being had to the accompanying drawings which are made a part thereof, and in which Figure 1 represents a side sectional view 30 through a two cycle engine and vapor heating passage, mixing valve, etc. Fig. 2 a front sectional view through the vapor heating passage and mixing valve, Figs. 3, 4 and 5 are sectional views through the mixing 35 valve, Fig. 6 is a top plan of the mixing valve, Fig. 7 a front sectional view through the carbureter valves, Fig. 8 a side sectional view through the carbureter, Fig. 9 a horizontal sectional view or plan of the carbureter and vapor heater, and Fig. 10 a perspective showing the carbureter and vapor heater and the relative position of the parts. Similar numbers refer to similar parts in the several views.

To illustrate the invention a two cycle type of engine has been employed though the apparatus on which priority of claims is based may be used on a four cycle engine as well, 1 is a cylinder, 2 the crank case, 3 the piston, 4 the connecting rod, 5 the inlet port, 6 the gas passage or by pass, and 7 the exhaust port of a two cycle internal explosive engine.

8 is an exhaust passage to which is connected the exhaust pipe 9. Lying within

this exhaust passage 8 is a return tube 10 through which the vaporized fuel is heated. 11 is an air port and 12 a mixing valve, the purpose of which is to mix air with the heated vapor before it passes into the mixing chamber 13 and the crank case 2. 14 is a carbureter attached to the lower end of the exhaust passage in such a manner that it connects directly into one end of the return tube 10. The other end of return tube 10 65 opens into the mixing valve 12.

It can be readily seen that other forms of vapor heaters may be used, as for instance a straight tube or spiral coil carried through the exhaust passage which, if of sufficient 70 length, will heat the vapor as well, and the only purpose of using the return tube shown is to obtain sufficient length of tube to properly heat the vapor.

The carbureter 14 is shown in detail in 75 Figs. 1, 7, 8, and 9 and is of the float type and is double, *i. e.* there are two compartments, one preferable for gasolene, the other for kerosene, distillate or other heavier fuel, the two portions being identical except that 80 it may be desired to use larger passages for the heavier oil, and a description of one will fit both. 15 is a supply pipe which feeds the float chamber 16. 17 is a cork float with a stem 18 passing through it, the upper end 85 19 passing through the cover 20 of the float chamber and serving as an indicator, the lower end terminating in a valve 21 which shuts off the supply of fuel when the float chamber is sufficiently filled and opens when 90 the float drops.

22 is a passage from the float chamber to the fuel duct 23, 24 is an air port through which air is drawn by the vacuum produced in the crank case or combustion chamber 95 of the engine. The air being drawn through port 24 passes over the fuel duct 23 at a high velocity and aerates or mixes the fuel by contact and absorption. This forms a rich vaporous mixture which then 100 passes into the valve 25 and from thence on into the heating tube 10.

Valve 25 is of the plug type but is provided with two inlets 26 and 27 and so arranged that when the opening is full from 105 one side the other side is completely closed, the object of this arrangement being so that fuel may be taken from one side or the other as desired. 28 and 29 are needle valves with thumb heads 30 and 31 by which the supply 110

of fuel may be adjusted or positively shut off from either side or both. After being aerated the rich mixture is then drawn through the outlet 32 of the carburetor into the return tube 10 through which it passes on to the mixing valve 12. In its passage through the return tube 10 the vapor is heated to a high temperature by the exhaust from the engine impinging against and passing around the tube on its way to the exhaust pipe.

Mixing valve 12 is of a rotary, cylindrical type with three ports. 33 is the gas inlet port and lies directly below the outlet of return tube 10 and is in the form of an oblong slot cut peripherally in the body of the valve. 34 is the air inlet port and is in the form of a longitudinal slot, and 35 is the outlet port for air and gas and for the greater portion of its length is also in the form of a longitudinal slot which joins the inlet port and becomes an extension of same as shown in Fig. 6.

The valve is constructed with ports of a proportionate size which repeated trial and experiment has demonstrated to be correct for the most efficient mixture of air and gas, and it is so arranged that when the valve is turned in the vertical position shown in Fig. 3 and as indicated by dotted line A, gas port 33, air port 34 and outlet port 35 are all open full. When the valve is turned toward the left as shown in Fig. 4 and indicated by dotted line B the air port 34 is entirely closed, gas port 33 still has a full opening owing to its slotted form, and outlet 35 is partially open. When in this position it will be noted that a rich mixture of fuel and air is drawn through the fuel canal into the engine. It is thus manifest that any position of the valve between the positions A and B allows a greater or less quantity of air to mix with the rich gas according to the angle of inclination from A to B. This feature is of use in starting, as a richer mixture is needed especially when the engine is cold.

When the valve is turned toward the right as shown on Fig. 5 and indicated by the dotted line C both gas port 33 and air port 34 are closed, the outlet 35 from the valve being partly open. This stops the engine by shutting off the fuel supply. It is thus manifest that any intermediate position of the valve between the positions B and C will affect the speed of the engine owing to the decreased fuel and air supply, and this feature is used to regulate the speed, the valve being operated by a hand lever or governor according to the type of engine. It will also be noted that the turning of the valve to the right cuts off the supply of both gas and air in the same proportion making the engine practically "fool proof". The subsequent action of the gases, explosion, etc., needs only a brief explanation, as the action in the con-

nection shown is that of an ordinary two cycle engine. The upward motion of the piston 3 produces a partial vacuum in the crank case 2 and when the inlet port 5 is uncovered the gas and air mixture rushes in. When the piston descends the mixture is compressed in the crank case. As soon as the exhaust port 7 is opened the burned gases exhaust into the heating passage and an instant later the mixture of air and gas rushes into the explosion chamber to be compressed and exploded.

In a four cycle engine the mixture of heated gas and air is drawn directly into the combustion chamber of the engine at each alternate revolution instead of into the crank case at each revolution in the two cycle engine.

In the drawings valve 12 is shown with a handle 36 which is turned by hand. In the stationary type of engine this valve will be operated by a governor (not shown) which will then automatically regulate the speed by varying the quantity of air and gas admitted to the crank case or combustion chamber. It is well known that a gasolene engine of the ordinary type will run for a time on kerosene or distillates after the engine is heated up, but the combustion chamber is very apt to become carbonized and dirty owing to the imperfect combustion. We have found that a gas produced from kerosene or other similar oils lacks stability when formed in the usual way of forming gasolene gas, and to be perfectly volatilized must be heated to a high temperature. We have found that it is impractical to mix the adequate amount of air and fuel for perfect combustion, then heat it and admit the heated mixture to the engine, as in the case of the two cycle engine where the heated gas is admitted to the crank case the revolving parts become overheated and proper lubrication is prevented, and in both the two cycle and four cycle engines, heating the mixture greatly reduces the volumetric efficiency of the gas. We have found also that the heated gas may be mixed with air at out door temperature with little loss from condensation and when so used the charge becomes much more effective when compressed and exploded.

What we claim and desire to protect by Letters Patent is:—

A multiple fuel carburetor having a body provided with a rearwardly projecting stem and with a central outlet opening extending therethrough and through said stem, said body also having separate oil chambers upon opposite sides of said outlet opening, said outlet opening having its counterbore at its forward end, said body also having ports projecting laterally in opposite directions from the outlet opening forwardly of the oil chambers, and vertical ports commu-

nicating with said lateral ports and open to the atmosphere, a hollow plug valve rotatable in said counterbore of the outlet opening and having openings in its wall for registry 5 with the said lateral ports, said body also having oil ports leading forwardly from the said oil chambers and provided with upright portions extending into the said lateral ports, and regulating valves threaded into 10 the body and movable into the upper ends of said vertical portions of said oil ports, to control communication between the latter and the said lateral ports.
